UNITED STATES PATENT OFFICE

FRANK B. ALLEN, OF LOWER MERTON TOWNSHIP, MONTGOMERY COUNTY, PENNSYLVANIA, ASSIGNOR, BY MESNE ASSIGNMENTS, TO THE ALLEN-SHERMAN-HOFF COMPANY, OF PHILADELPHIA, PENNSYLVANIA, A CORPORATION OF PENNSYLVANIA

STORAGE TANK FOR ASHES

Application filed May 17, 1928. Serial No. 278,610.

This invention relates to a receptacle for liquid and solid materials. More particularly it relates to a storage tank for receiving and separating mixed solid and liquid materials.

It has been customary in handling solid materials, such as incombustible residues, to conduct a mixture of the same with liquid to a receptacle where it is stored until it can be hauled away. Means have been suggested for separating the liquid and solid materials so that they could be removed separately from the receptacle but, so far as I am aware such means have not been entirely satisfactory for all conditions and materials, partly because of clogging of the liquid separating and withdrawing means.

It is an object of this invention to provide an improved construction of storage tank for mixed solid and liquid materials in which the solid and liquid materials can be separated without any danger of stoppage and without spillage of liquid due to such stoppage.

Another object is to provide a storage tank of improved simplified construction for positively separating mixed solid and liquid materials, and having improved means for separately conducting off the liquid materials.

Other objects will be apparent from the specification and from the accompanying drawings in which latter:

Fig. 1 is a longitudinal sectional view through the device;

Fig. 2 is a transverse sectional view taken along the line 2—2 of Fig. 1;

Fig. 3 is a detail perspective view greatly enlarged of a portion of the end of the device as seen from the line 3—3 of Fig. 1.

Referring particularly to the drawings, in its preferred embodiment the device comprises a base 1 mounted upon suitable supports 2. Side walls 3 project upwardly from the base. A shell 5 is supported within the side walls in spaced relation to the base by means of angle bars 6 which rest upon upstanding shoulders 7 carried by the base. Braces 8 further support the shell 5 from the base. The shoulders 7 project upwardly above the bottom of the shell 5 and in spaced

relation thereto, extending beyond solid receiving position with respect to the bottom of the shell. The surfaces of the shoulders 7 adjoining the shell 5 are inclined downwardly at an angle greater than the angle of repose of solid materials and terminate adjacent discharge openings in the base. The side walls of the shell are inclined inwardly and downwardly to the discharge openings as can be seen in Fig. 2. Movable gates 10 are provided for the discharge openings. A portion of the liquid contained in the tank is adapted to be directed by the gates 10 into stationary troughs 11 from which it is conducted by means of conduits 12. A conduit 13 admits a mixture of solid and liquid material into the shell. Conduits 14 open downwardly into the upper portion of the space between the shell 5 and the side walls 3 and are adapted to discharge the liquid therefrom. Other conduits 15 communicate with the bottom of this space and with the conduits 12. Solid materials discharged through the discharge openings can be collected in the vehicles 13 and drawn away. A chute can be provided for directing the solid material into the vehicle.

In the operation of the device a mixture of solid and liquid material is conducted into the solids-retaining, open-bottom shell 5. The solids settle upon the portion of the base within the shell and a portion of the liquid drains away through the trough 11 and conduit 12. Other liquid passes between the shoulder 7 and the walls of the shell into the space between the shell and the side walls 3. Liquid accumulating in this space is substantially free from solid material particularly of the larger sizes and can be conducted away by means of the conduits 14 and 15. The solid material within the shell can be dropped when desired through the discharge openings into the vehicles disposed therebeneath, the solid material upon the inclined surface of shoulder 7 being discharged at the same time.

While a specific embodiment of the invention has been shown and described it will be understood that modifications can be made therein within the spirit and scope of the invention and such modifications are in-

tended to be covered by the appended claims:

1. A tank for mixed solids and liquids comprising a container for solids and liquids including a base and upstanding side walls, the base having a discharge opening, a movable gate for the opening, means adjacent said opening for continuously collecting and carrying away a portion of the liquid in said tank, a solids-retaining, open-bottom shell supported within and in spaced relation to the side walls and communicating through liquid carrying passages with the space in the container outside of the shell, a shoulder projecting upwardly from said base to a point above the bottom edge of said shell and extending around the bottom of said shell, said shoulder and shell being spaced to provide said liquid carrying passages while substantially preventing the passage of solids from said shell and means including a conduit for removing liquid from the space between the side walls and shell.
2. A tank for mixed solids and liquids comprising a container including a base and upstanding walls, the base having a discharge opening, a movable gate for the opening, means adjacent said opening for continuously collecting and carrying away a portion of the liquid in said tank, a solids-retaining, open-bottom shell supported within and in spaced relation to the side walls and communicating through liquid carrying passages with the space in the container outside of the shell, a shoulder projecting upwardly from said base to a point above the bottom edge of said shell and extending around the bottom of said shell, said shoulder and shell being spaced to provide said liquid carrying passages while substantially preventing the passage of solids from said shell and means including a conduit for conducting liquid from the space between the side walls and shell, the inlet of said conduit being in spaced relation to the base.
3. A storage tank comprising a container for solids and liquid including a base and upstanding side walls, the base having a discharge opening, a movable gate for the opening, means adjacent said opening for continuously collecting and carrying away a portion of the liquid in said tank, a solids-retaining, open-bottom shell supported within and in spaced relation to the side walls and communicating through liquid carrying passages with the space in the container outside of the shell, a shoulder projecting upwardly from said base to a point above the bottom edge of said shell and extending around the bottom of said shell, said shoulder and shell being spaced to provide said liquid carrying passages while substantially preventing the passage of solids from said shell, the inner surface of the shoulder exteriorly of the shell being upwardly and outwardly inclined, and means including a conduit for

removing liquid from the space between the side walls and shell.

4. A storage tank comprising a container for solids and liquid including a base and upstanding side walls, a solids-retaining open bottom shell supported within and in spaced relation to the side walls and communicating through liquid carrying passages with the space in the container outside of the shell, a shoulder projecting upwardly from said base to a point above the bottom edge of said shell and extending around the bottom of said shell, said shoulder and shell being spaced to provide said liquid carrying passages while substantially preventing the passage of solids from said shell, the inner surface of the shoulder exteriorly of the shell being inclined upwardly and outwardly at an angle greater than the angle of repose of the solid material, the base being provided with a discharge opening adapted to receive the solid material from the inclined surface, a movable gate for the discharge opening, a liquid collecting trough adjacent said opening, means including a conduit for removing liquid from the space between the side walls and shell and means for conducting liquid from said trough.
5. A storage tank comprising a container for solids and liquids including a base and upstanding side walls, the base having a discharge opening, a movable gate for the opening, a liquid collecting trough adjacent said opening, a solids-retaining open bottom shell supported within and in spaced relation to the side walls and communicating through liquid carrying passages with the space in the container outside of the shell, a shoulder projecting upwardly from said base to a point above the bottom edge of said shell and extending around the bottom of said shell, said shoulder and shell being spaced to provide said liquid carrying passages while substantially preventing the passage of solids from said shell, means including a conduit for removing liquid from the space between the side walls and shell and means for conducting liquid from said trough.
6. A storage tank comprising a container for solids and liquid including a base and upstanding side walls, a solids-retaining open bottom shell supported within and in spaced relation to the side walls and communicating through liquid carrying passages with the space in the container outside of the shell, a shoulder projecting upwardly from said base to a point above the bottom edge of said shell and extending around the bottom of said shell, said shoulder and shell being spaced to provide said liquid carrying passages while substantially preventing the passage of solids from said shell, said shoulder having its inner surface inclined upwardly and outwardly at an angle greater than the angle of repose of the solid material, the base

- being provided with a discharge opening adapted to receive the solid material from the inclined surface, a movable gate for the discharge opening, a liquid collecting trough adjacent said opening, means including a conduit for removing liquid from the space between the side walls and shell and means for conducting liquid from said trough.
7. A tank for mixed solids and liquids comprising a base having a discharge opening, a movable gate for said opening, upwardly extending side walls around the outer edge of said base, a shoulder projecting upwardly from said base within said side walls, a shell supported within and in spaced relation to said side walls and having its lower edge within said shoulder and spaced therefrom to provide a fluid passage between the inside of said shell and the space between the outside of said shell and said side walls, said shell being spaced from said shoulder a distance great enough to permit free flow of liquid therebetween while substantially preventing the passage of solid material therebetween, and means including a conduit for conducting liquid from the space between the side walls and the shell.
